UNITED STATES PATENT OFFICE.

CHARLES E. SPENCER, OF CHICAGO, AND OWEN W. ROBERTS, OF OAK PARK, ILLINOIS,
ASSIGNORS TO CASEMENT HARDWARE CO., OF CHICAGO, ILLINOIS, A CORPORATION
OF ILLINOIS.

DESIGN FOR A CASEMENT-WINDOW OPERATOR.

Application filed April 23, 1927. Serial No. 21,708. Term of patent 14 years.

To all whom it may concern:

Be it known that we, CHARLES E. SPENCER and OWEN W. ROBERTS, citizens of the United States, residing at Chicago and Oak Park, in the county of Cook and State of Illinois, respectively, have invented a new, original, and ornamental Design for Casement-Window Operators, of which the following is a specification, reference being had to the accompanying drawing, forming part thereof.

Fig. 1 is a plan view of a casement window operator showing our new design;

Fig. 2 is a front elevational view of the same; and

Fig. 3 is a side elevational view taken from the right of Fig. 1.

We claim:

The ornamental design for a casement window operator, as shown.

In witness whereof, we hereunto subscribe our names this 20th day of April, 1927.

CHARLES E. SPENCER.
OWEN W. ROBERTS.
